(57) **CLAIM**

The ornamental design for an attachment for a cleaning device, as shown and described.

DESCRIPTION

FIG. 1 is a perspective view of a first embodiment of an attachment for a cleaning device showing our new design;

FIG. 2 is a left side view thereof;

FIG. 3 is a top plan view thereof;

FIG. 4 is a bottom plan view thereof;

FIG. 5 is a right side view thereof;

FIG. 6 is a rear elevational view thereof;

FIG. 7 is a front elevational view thereof;

FIG. 8 is a perspective view of a second embodiment of an attachment for a cleaning device showing our new design;

FIG. 9 is a right side view thereof;

FIG. 10 is a top plan view thereof;

FIG. 11 is a bottom plan view thereof;

FIG. 12 is a left side view thereof;

FIG. 13 is a rear elevational view thereof; and,

FIG. 14 is a front elevational view thereof.
